PACKING MACHINE

Karl Jens Sylvest and Ejler Jensen, Copenhagen,
Denmark, assignors to F. L. Smidt & Co., New
York, N. Y., a corporation of New Jersey

Application June 4, 1949, Serial No. 97,266
In Great Britain June 14, 1948

12 Claims. (Cl. 222—168)

1

This invention relates to apparatus for packing powdered materials of the kind which includes a tank rotating upon a vertical axis and having a number of outlet openings at its lower end leading to filling spouts on which bags can be mounted. More particularly, the invention is concerned with a novel packing apparatus of the rotary tank type, which is so constructed that a regular flow of the material through the spouts is obtained without the use of a rotary agitator and little or no air need be supplied to the material within the tank, either at the start or during continued operation.

In prior packing apparatus including a rotary tank, it is common to employ an agitator, which rotates within the tank at a speed substantially greater than that of the tank, and to introduce air into the tank, in order to obtain a steady discharge of material. The use of such an agitator, however, is undesirable, in that it requires a separate motor and drive and this complicates the machine. If the agitator is not used, it is not possible to obtain a sufficiently uniform discharge of material, even if the air is diffused into the tank in a finely divided state. In the prior apparatus having the air supply only, it has been found necessary to use larger quantities of air during starting than during continuous operation and the increased use of the air causes irregular discharge for a period immediately after the machine is put into operation. Also, during that period, a longer time is required to fill bags attached to the spouts, so that, whereas in regular operation, a bag is filled during one revolution of the tank, the bag may have to make two revolutions with the tank in order to be filled. In addition, the emptying of the tank of the prior apparatus after the completion of a packing operation has been found to require that all outlet openings be employed for the purpose, and this results in the production of a number of partially filled bags.

The present invention is directed to the provision of a novel packing apparatus of the rotary tank type, which does not involve the use of a rotating agitator and may be operated with less air than has heretofore been required and, in some forms, without the use of air, either during starting or prolonged operation.

The apparatus of the invention includes a stationary scraper or distributing device projecting into the tank and provided with scraping elements lying close to the inner ends of the outlet openings and overlying preferably only a narrow annular area along the periphery of the bottom

2

of the tank containing the openings. As the tank rotates, the distributing device produces a regular flow of material through the outlets, the elements agitating the material around and above the openings. With certain materials, such as some types of cement, it has been found possible to obtain a constant discharge rate, even though no air is employed. Also complete emptying of the tank through a single outlet can be effected.

10 The apparatus includes means for preventing contact of the material with the bottom of the tank except over a narrow annular area along the periphery of the bottom of the tank containing the outlet openings and underlying the scraping elements. For this purpose, the bottom of the tank may carry a central cone of a diameter not greatly less than the bottom, or the distributing device may include such a cone. As an alternative, the device may include radial arms lying close to the upper surface of the bottom and partly covered by a circular plate or partly covered by a combination of a plate and a cone.

15 For a better understanding of the invention, reference may be made to the accompanying drawing, in which:

Fig. 1 is a view, partly in vertical section and partly in elevation, of one form of the apparatus;

Fig. 2 is a fragmentary vertical sectional view of the apparatus taken on the line 2—2 of Fig. 3;

Fig. 3 is a sectional view on the line 3—3 of Fig. 2;

Fig. 4 is a fragmentary vertical sectional view on the line 4—4 of Fig. 5 of a modified form of the apparatus;

Fig. 5 is a sectional view on the line 5—5 of Fig. 4;

Fig. 6 and 7 are vertical sectional views of other modified forms of the apparatus; and

Fig. 8 is a vertical sectional view of another modified form of the apparatus.

20 The packing apparatus illustrated in Fig. 1 comprises a tank 10 of generally cylindrical form with a tapering upper end. A shaft 11 extends vertically through the tank and is suspended at its upper end in a bearing 12, the shaft being driven by any appropriate means (not shown). The tank rests on its bottom on plate 13 encircling the shaft and held in place by nuts 14 threaded on the shaft. The upper end of the tank is closed by a stationary cover made up of a plate 15 and a cylindrical section 16, the plate resting on suitable supports 17 and the section extending past the supports and into the open upper end of the tank. The plate 15 is provided

with an inlet 18 through which material may be supplied to the tank.

The bottom of the tank is provided with a plurality of outlet openings 19 spaced along the periphery thereof and a rubber outlet spout 20 leads from each outlet opening and delivers the material to a filling spout 21. The lower end of spout 21 is constructed to carry a receptacle, which may be a valve bag held in place on the spout by a gripping element 22. The filling spout is suspended from a weigh-beam 23 and, when the filled bag is to be released from the filling spout, the gripper is freed from the bag by engagement of a roller 24 with a fixed guide rail 25. The filling spouts and related parts form no part of the present invention and may be of the construction illustrated and described in Middelboe Patent 1,903,188, issued March 28, 1933.

In the apparatus illustrated in Fig. 1, the material supplied to the interior of the tank through inlet 18 is kept from contact with the bottom of the tank except along a narrow peripheral area containing the outlet openings. For this purpose, a conical member 26 rests upon the bottom and is attached at its upper end to shaft 11. The space defined by the bottom of the tank and the conical member may be used for an air reservoir, the air being supplied through a connection 27 leading into the hollow lower end of the shaft to escape beneath the conical member through ports 28. The air is then supplied by connections 29 to means for supplying the air in diffused condition to the material above and adjacent the outlet openings. In the construction shown in Figs. 1 and 2, the diffusing means are concentric pipes 30 lying on the bottom of the tank outside the conical member and on either side of the row of outlet openings. The pipes may be of porous material or may be perforated and covered with porous material so as to effect proper diffusion of the air.

A stationary scraping or distributing device is mounted in the tank and includes scraping elements lying immediately above the outlet openings. In the construction shown in Fig. 1, the device comprises a plurality of bars 31 attached at their upper ends to the cover and extending downwardly along the shaft and the conical member 26, the group of bars being connected by rings 32, 33, 34. Scraping elements 35 are attached to the lower ring 34 with a spacing equal to that between the outlet openings and each element in the construction shown is of U-shape with its legs 35a extending radially outwardly from shaft 11. The scraping elements lie a short distance above pipes 30 and their legs terminate close to the inner cylindrical wall of the tank.

In the construction shown in Figs. 4 and 5, the narrow peripheral areas of the bottom of the tank between adjacent outlet openings 19 are cut away to form openings in which are inserted porous plates 36, and a chamber 37 is attached to the bottom of the tank below each plate and is supplied with air through a connection 38 from the air reservoir defined by the bottom of the tank and the conical member 26. The air supplied to each chamber 37 escapes through the porous plate 36 at the top of the chamber to enter the material lying on the plate.

In the construction shown in Fig. 6, the bottom of the tank is provided with a conical member 39 and the distributing device comprises a plurality of bars 40, which are attached at their upper ends to the stationary cover and extend

downwardly along the shaft and along the conical member 39. At their lower ends, the bars have radial portions 41 lying close to the bottom of the tank and these portions are covered by a plate 42, which is of less outer diameter than the diameter of the bottom of the tank. The material is thus kept from contact with the bottom of the tank except along a narrow peripheral area thereof and, in this area, are formed the outlet openings 43. The ends of sections 41 of the bars projecting beyond the edge of plate 42 overlie the peripheral area of the bottom containing the outlet openings and act as scraping elements.

In the construction shown in Fig. 7, the scraping device comprises a plurality of bars 44 attached at their upper ends to the stationary cover of the tank and extending downwardly parallel to the shaft. At the lower ends, the bars are attached to a plate 45, which is of slightly less diameter than the bottom of the tank, so that the material is kept from contact with the bottom except along a narrow peripheral area thereof. Outlet openings 46 are formed in this area and plate 45 is provided with scraping elements 47 projecting beyond the margin of the plate and overlying the narrow peripheral area of the bottom containing the outlet openings.

The construction shown in Fig. 8 is similar to that of Fig. 7 except that the flat plate 45 is replaced by a conical member 48 attached to the lower ends of bars 49 suspended from the cover of the tank. The bottom of the cone 48 is of slightly less diameter than the bottom of the tank, so that the material is kept from contact with the tank except along a narrow peripheral area containing the outlet openings 50. A plurality of scraping elements 51 are attached to the lower end of cone 48 and extend outwardly parallel to the bottom to overlie the narrow exposed area thereof.

In the different forms of apparatus illustrated, the material resting on the narrow peripheral area of the bottom is agitated during rotation of the tank by the stationary scraping elements and a regular flow of the material through the outlet openings results. With certain materials, such as some cements, discharge of the material at a constant rate is obtained without supplying air to the material. When the tank is to be completely emptied, only a single outlet opening need be employed since the material on the narrow area is continually leveled off and thus flows through the open outlet opening as the tank rotates.

In the forms of apparatus shown in Figs. 6, 7, and 8, the provision of the means, such as plates 42 and 45 and cone 48, for relieving the load on the bottom of the tank makes it possible to start the full tank without the use of any air supply. However, these forms of apparatus may be provided with air supply devices, such as are shown in Figs. 1-5, inclusive. Also, the apparatus shown in Fig. 1 may be employed without the air supply means for some purposes.

We claim:

1. In apparatus for packing powdered material, the combination of a filling tank comprising a side wall and a bottom rigidly secured thereto, the tank being mounted for rotation on a central vertical axis through the bottom of the tank and having an open upper end and outlet openings at its lower end spaced about the periphery of the tank, a stationary closure for the upper end of the tank, and scraping elements within the

tank and rigidly connected to the closure, the elements lying close to the inner ends of the outlet openings.

2. In apparatus for packing powdered material, the combination of a filling tank comprising a side wall and a bottom rigidly secured thereto, the tank being mounted for rotation on a central vertical axis through the bottom of the tank and having an open upper end and outlet openings at its lower end spaced about the periphery of the tank, means within the tank preventing the material from coming in contact with the bottom of the tank except over a narrow annular area along the periphery of the bottom adjacent the openings, a stationary closure for the upper end of the tank, and stationary scraping elements mounted within the tank and rigidly connected to the closure, the elements lying close to the inner ends of the openings.

3. In apparatus for packing powdered material, the combination of a filling tank comprising a side wall and a bottom rigidly secured thereto, the tank being mounted for rotation on a central axis through the bottom of the tank and having an open upper end and outlet openings in its bottom spaced about the periphery thereof, means within the tank preventing the material from coming in contact with the bottom of the tank except over a narrow annular area along the periphery of the bottom containing the outlet openings, a stationary closure for the upper end of the tank, and stationary scraping elements mounted in the tank to overlie said narrow area adjacent the openings, the elements being rigidly connected to the closure.

4. In apparatus for packing powdered material, the combination of a filling tank comprising a side wall and a bottom rigidly secured thereto, the tank being mounted for rotation on a central vertical axis through the bottom of the tank and having an open upper end and outlet openings at its lower end spaced about the periphery of the tank, a stationary closure for the upper end of the tank, and means attached to the closure for preventing the material from coming into contact with the bottom of the tank except over a narrow annular area along the periphery of the bottom adjacent the openings, said means including stationary scraping elements overlying the annular area adjacent the openings.

5. In apparatus for packing powdered material, the combination of a filling tank comprising a side wall and a bottom rigidly secured thereto, the tank being mounted for rotation on a central vertical axis through the bottom of the tank and having an open upper end and outlet openings at its bottom spaced about the periphery thereof, means within the tank preventing the material from coming in contact with the bottom of the tank except over a narrow annular area along the periphery of the bottom containing the outlet openings, means for diffusing air into the material lying on said area, a stationary closure for the top of the tank, and stationary scraping elements mounted in the tank to overlie said area adjacent the openings, the elements being connected to the closure.

6. In apparatus for packing powdered material, the combination of a filling tank comprising a side wall and a bottom rigidly secured thereto, the tank being mounted for rotation on a central axis through the bottom of the tank and having an open upper end and outlet openings in its bottom spaced about the periphery thereof, a conical member within the tank for directing

the material upon an annular area along the periphery of the bottom containing the outlet openings, means for diffusing air into the material lying on said area, a stationary closure for the top of the tank, and stationary scraping elements overlying the annular area adjacent the openings, the elements being connected to the closure.

7. In apparatus for packing powdered material, the combination of a filling tank comprising a side wall and a bottom rigidly secured thereto, the tank being mounted for rotation on a central axis through the bottom of the tank and having an open upper end and outlet openings in its bottom spaced about the periphery thereof, a conical member mounted centrally on the bottom of the tank for directing the material upon an annular area along the periphery of the bottom containing the outlet openings, a stationary closure for the top of the tank, and stationary scraping elements overlying the annular area adjacent the openings, the elements being connected to the closure.

8. In apparatus for packing powdered material, the combination of a filling tank comprising a side wall and a bottom rigidly secured thereto, the tank being mounted for rotation on a central axis through the bottom of the tank and having an open upper end and outlet openings in its bottom spaced about the periphery thereof, a conical member mounted centrally on the bottom of the tank for directing the material upon an annular area along the periphery of the bottom containing the outlet openings, means for diffusing air through the bottom of the tank into the material on said annular area, means for supplying air into the interior of the conical member, and connections between the interior of the conical member and the diffusing means.

9. In apparatus for packing powdered material, the combination of a filling tank comprising a side wall and a bottom rigidly secured thereto, the tank being mounted for rotation on a central axis through the bottom of the tank and having an open upper end and outlet openings in its bottom spaced about the periphery thereof, a conical member mounted centrally on the bottom of the tank for directing the material upon an annular area along the periphery of the bottom containing the outlet openings, a stationary closure for the top of the tank, and stationary scraping elements depending from the closure and having sections overlying the annular area adjacent the openings.

10. In apparatus for packing powdered material, the combination of a filling tank comprising a side wall and a bottom rigidly secured thereto, the tank being mounted for rotation on a central axis through the bottom of the tank and having an open upper end and outlet openings in its bottom spaced about the periphery thereof, a stationary closure for the upper end of the tank, and means depending from the closure for preventing the material from coming into contact with the bottom of the tank except over a narrow annular area along the periphery of the bottom adjacent the openings, said means including stationary scraping elements overlying said area adjacent the openings.

11. In apparatus for packing powdered material, the combination of a vertical shaft, a bearing for the shaft above the lower end thereof, a tank supported on the lower end of the shaft, the tank having an open upper end, through which the shaft extends, and outlet openings ad-

jaçent its lower end, a stationary closure for the upper end of the tank, the shaft extending through the closure, means for supporting the closure, and scraping elements rigidly attached to the closure and extending down into the tank and terminating near the outlet openings.

12. In apparatus for packing powdered material, the combination of a vertical shaft, a bearing for the shaft above the lower end thereof, a tank supported on the lower end of the shaft, the tank having an open upper end, through which the shaft extends, and outlet openings adjacent its lower end, a stationary closure for the upper end of the tank, the shaft extending through the closure, means for supporting the closure, means within the tank preventing the material from coming into contact with the bottom of the tank except over a narrow annular area along the periphery of the lower end of the tank adjacent the outlet openings, and scraping elements rigidly attached to the closure and extending down into the tank and terminating adjacent said area.
